(57) **CLAIM**

The ornamental design for a pour spout, as shown and described.

DESCRIPTION

FIG. 1 is a top perspective view of the present invention; FIG. 2 is a bottom perspective view of the present invention shown in FIG. 1;

FIG. 3 is a front elevational view of the present invention shown in FIG. 1;

FIG. 4 is a back elevational view of the present invention shown in FIG. 1;

FIG. 5 is a side elevational view of the present invention shown in FIG. 1;

FIG. 6 is a top plan view of the present invention shown in FIG. 1; and,

FIG. 7 is a bottom plan view of the present invention shown in FIG. 1.

The broken lines in the drawings depict environmental subject matter only and form no part of the claimed design.
